UNITED STATES PATENT OFFICE

EARL G. GRIFFITH, OF HUNTINGTON PARK, CALIFORNIA

BOX DELIVERY DEVICE

Application filed December 26, 1931. Serial No. 583,199.

My invention relates to the art of article handling and more particularly to devices for delivering boxes one by one to a given station in timed relation with another means 5 for removing said boxes from said station.

Many devices of the general nature above referred to have been devised in the past, but none of these is proof against breaking the boxes or upsetting these, and it is an important object of my invention to provide a box delivery device which eliminates the faults mentioned.

Most of the damage done to boxes by box delivery devices at present in general use, result 15 from non-positive feeding of a box to a power driven conveying means. Thus if the non-positive mechanism slips on the box for some reason or another, the box will not be properly positioned for engagement by 20 the positive conveying means and the result will be a broken box or a broken delivery device.

It is another object of my invention to provide a box delivery device which positively 25 feeds boxes one at a time to a delivery station but which is proof against improper positioning of boxes to be acted upon by the positive feed means.

The manner of accomplishing the foregoing objects, as well as further objects and advantages, will be made manifest in the following description taken in connection with the accompanying drawing, in which:

Fig. 1 is a diagrammatic plan view of a 35 preferred embodiment of a delivery device of my invention.

Fig. 2 is a side elevational view of Fig. 1 taken in the direction of the arrow 2.

Figs. 3 and 4 are transverse sectional views 40 taken respectively on the lines 3-3 and 4-4 of Fig. 1.

Referring specifically to the drawing, a preferred embodiment of my invention is seen in a box delivering device 10 which receives boxes from a conveyer 11 and delivers these one at a time to a box elevator 12.

The delivery device 10 includes a frame 15, including legs 16, 17, 18, 19, 20 and 21. Connecting the legs 16, 17 and 18 is an upper longitudinal frame member 23, while a

lower frame member 24 connects the legs 16 and 17. Connecting the legs 19 and 20 and disposed opposite the members 23 and 24 are longitudinal frame members 25 and 26. Connecting upper ends of the legs 16 and 19 55 is a transverse frame member 28. Disposed beneath members 27 and 28, and connecting the same pairs of legs respectively, are transverse frame members 29 and 30. The members 29 and 30 support a longitudinal angle 60 iron 32 by its opposite ends.

Supported on the legs 18 and 21 and the transverse frame member 28 is a U-shaped frame 35 which, with the longitudinal frame member 23, supports rotatably a pair of idle 65 rollers 36. Also supported on the transverse member 28 and U-shaped frame 35 is a guard bar 38 having stops 39 and 40 at its opposite ends. The upper ends of the legs 19 and 20 project above the longitudinal member 26 70 and support a guide member 45.

An adjacent end of the conveyer 11 is adapted to be supported on the cross frame member 27, this conveyer being shown as an ordinary gravity conveyer having a guard 75 46 on one side and a guard 47 on the other, the latter having its forward end supported on the upper end of the post 19.

Supported at their opposite ends on transverse frame members 27 and 28 is a pair of longitudinal frame members 49 and 50. Pivotally supported in horizontal position by their opposite ends on the horizontal, longitudinal frame members 23 and 50 is a power 80 driven roller 55 and an idle roller 56. The roller 55 has a suitable sprocket at one end thereof by which it is adapted to be driven.

Disposed longitudinally between the frame members 25 and 49 is an idle roller 58 which is supported at its opposite ends on these frame members. Also pivotally mounted between frame members 25 and 49 is a short roller 59 with its axis disposed transversely. The rollers 36, 55, 56, 58 and 59 are preferably all on the same level, or at least substantially in the same plane.

Journalled in suitable bearings mounted on longitudinal frame members 25 and 50 is a short shaft 65 having a sprocket 66 fixed 95 on its outer end and a sprocket 67 fixed thereon 100

on between the longitudinal frame members 49 and 50, as clearly shown in Figs. 1 and 4. Journalled in suitable bearings provided on the opposite ends of the frame members 25 5 and 50 from the shaft 65 is a short shaft 69 having a sprocket 70. Trained around the sprockets 67 and 70 is a chain 71 which is preferably provided with box pushing rollers 75, these rollers being disposed on diametrically opposite portions of said chain. 10

Swingably mounted in brackets 77 provided on the inner face of the longitudinal frame member 23 are upright arms 78 and 79 of a box pusher 80. Rotatably mounted 15 between the arms 78 and 79 is a horizontal roller 81. Mounted on a vertical axis on the upper end of the arm 78 is a flat roller 85.

Connecting upper ends of the arms 78 and 79 is a bar 87 which is connected by a spring 20 88 to a finger 89 fixed upon the longitudinal frame member 23, for a purpose which will be made manifest hereinafter. Connecting lower ends of the arms 78 and 79 is a shaft 90 carrying rollers 91.

25 Disposed longitudinally within the frame 15 and journalled in suitable bearings provided on the transverse frame members 29 and 30 is a cam shaft 95 carrying a clutch 96 and a pair of cams 97, the cams 97 being disposed opposite the rollers 91, which are maintained in contact with these cams by the spring 88. The shaft 95 is adapted to turn in the direction of the arrow 98 to swing the box pusher 80 from its full line 30 position as shown in Fig. 3 to its dotted line position therein, and then permit a quick return to the full line position.

The clutch 96 is of the single revolution type and includes a cylindrical outer shell 40 100 which rotates idly on the shaft 95 and is provided with a bevel ring gear 101 for driving the shell 100. Formed on the inner surface of the shell 100 is a driving notch 103. Keyed onto the shaft 95 and disposed with 45 in the shell 100 is a driven hub member 105 having a dog 106 which is spring urged outwardly into contact with the inner surface of the shell 100 so that when released the dog 106 engages the notch 103 as soon as this is 50 rotated opposite this dog, further rotation of the shell 100 being imparted to the shaft 95 as long as the dog 106 remains in the notch 103.

Journalled vertically in a suitable bearing 55 110, provided on the inner surface of the longitudinal frame member 23, as shown in Fig. 4, is a clutch control shaft 111 having a box contacting arm 112 at its upper end and a clutch actuating arm 113 at its lower 60 end. Also there is a spring 114 wound about the shaft 111, this being connected with the frame 15 and the shaft so as to continually urge the clutch actuating arm 113 into such a position that whenever the hub 105 is rotated so as to bring the dog 106 upwardly, 65

this dog engages the arm 113 and is depressed out of the notch 103, thereby causing rotation of the shaft 95 to halt. When the arm 113 is in this position the arm 112 extends as shown in Fig. 1, and when the arm 112 is swung in a clockwise direction so as to come in contact with the stop 39, this swings the arm 113 out of engagement with the dog 106 and permits it to be spring urged upwardly into engagement with the interior face of the cylindrical clutch shell 100. 75

Extending transversely of the frame 15 and journalled in a suitable bearing 120 fixed on the longitudinal frame member 32, and a bearing 121 mounted on an external standard 122, is a drive shaft 125 having sprockets 126, 127 and 128, and a bevel pinion 129, the latter meshing with the bevel ring gear 101 of the clutch 96. The sprocket 127 is connected to the sprocket 66 by a chain 130, while the sprocket 128 is connected to the sprocket of the driven roller 55 by a chain 131. 80

85 The structure of the delivery device 10 having thus been completely described, it is noted that the elevator 12 is merely diagrammatically shown herein, and comprises a shaft 140 carrying a sprocket 141 which operates with a similar sprocket (not shown) which is disposed thereabove, to support a chain 142 carrying box carriages 145. The box carriages 145 each have a pair of arms 146 and the path of the chain 142 is such that the arms 146 pass upwardly on opposite sides of the U-shaped frame 35 so that whenever a box is disposed over this frame and supported on the rollers 36 thereof, it is lifted upwardly by a carriage 145 passing this frame. 95

99 Also provided on the shaft 140 is a sprocket 150 which is connected by a chain 151 through a sprocket 126 on the shaft 125 so that this shaft is driven in timed relation with the elevator 12. The ratio of this drive is such that the shell 100 of the clutch 96 is given a single rotation during each interval between the passage of successive box carriages 145 past the U-shaped frame 35. 105

110 The operation of my invention is as follows:

Assuming that the elevator 12 is continuously driven at a constant rate of speed, the shaft 125 is of course driven in a like manner. 115

Owing to the spring 114 rotating the shaft 111 so as to keep the arm 113 in position to be engaged by the clutch dog 106, the clutch 96 is normally disconnected and the box pusher 80 remains in its upward position as shown in full lines in the drawing. Boxes are fed from the conveyer 11 to the box delivery device 10 regularly or intermittently 120 as the case may be, but these boxes are never positively fed to the deliver device but are preferably fed by gravity or by a yieldable power driven conveyer. The boxes, of course, are fed in sequence and the foremost 125 130

box, when it comes in contact with the roller 55 which rotates continuously, is drawn into the device, rolling upon the idle rollers 56 until it reaches the position indicated by the 5 dotted line 200 in Fig. 2, this position being hereinafter referred to as the timing station.

When a box moves into the timing station it necessarily engages the arm 112 and swings the shaft 111 so as to disengage the arm 113 10 from the clutch dog 106. After this response to the positioning of the box in the timing station, the box remains in this station until the notch 103 comes around into engagement with the dog 106, whereupon the pusher 80 15 is depressed into its dotted line position and pushes the box from the timing station over the chain 71 onto the roller 58 and into the path of the roller 75 which is coming up into position to engage this box. This roller 20 75 then engages the box disposed over the chain 71, and propels this box in the direction traveled by the chain until the box arrives against the stop 40, as shown in full line in Figs. 1 and 2, this position being herein- 25 after referred to as the "delivery station".

The chain 71 runs continually in timed relation with the elevator 12, and at such a speed that any box propelled as just described by one of the rollers 75 into the delivery station 30 arrives at this station just in time to be lifted by one of the box carriages 145 of the elevator 12.

It is to be understood, of course, that while I prefer the positive feed as embodied in the 35 chain 71, the use of a plurality of power driven rollers beneath the boxes in the delivery device which would propel each box to the delivery station just as soon as this box has been pushed clear of the stop 39, might 40 be substituted in place of the positive feed means.

One of the special advantages of my invention is the impossibility of shifting any box towards the chain 71 in the path of a feed 45 roller 75 excepting during those intervals when these rollers are disposed away from over the chain 71 so that a box may be properly fed into position over this chain. Furthermore, whenever a box is thus fed over the 50 chain 71 there is no obstruction possible to prevent it being properly fed directly to the delivery device 10, and the operation of the device continues as above described.

While the position of the box in the path of 55 the elevator carriages 145 is herein referred to as the "delivery station", the position of the box as it is fed into the path of one of the rollers 75 might also be considered as the delivery station.

60 What I claim is:

In combination: means forming a delivery station; means for removing boxes from said delivery station one by one; a continuously operating feed means for delivering boxes 65 positively to said delivery station, said feed

means operating in timely relation with said box removing means; means for conveying a series of boxes one by one to a timing station which is outside the path of said positive feed means; and means responsive to the arrival of a box at said timing station to shift said box into the path of said feed means, said shifting means operating in timely relation with said feed means and being normally inoperative until rendered operative by said box 70 arriving at said timing station.

In testimony whereof, I have hereunto set my hand at Los Angeles, California, this 11 day of Dec., 1931.
